WINDMILL CONTROL

Robert C. Robson, Juno, and Charles G. Robson,
La Grange, Tex.

Application January 10, 1938, Serial No. 184,308

1 Claim. (CL 220—1)

This invention relates to means for controlling the operation of windmills or other motors utilized for the purpose of pumping liquids.

An object of the invention is to utilize a portion of the elevated liquid as a means for operating the brake mechanism of the motor, said portion of the elevated liquid being utilized automatically as soon as the liquid within a storage tank or the like has been brought to a predetermined level by the operation of the motor.

A further object is to provide apparatus of this character which can be installed readily, is simple in construction, and can be produced at low cost.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred form of the invention has been shown.

25 In said drawings

Figure 1 is a view partly in elevation and partly in section showing the complete apparatus constituting the present invention.

Figure 2 is a similar view of a portion of the apparatus showing the relative positions of the parts while the storage reservoir is being filled.

Figure 3 is a perspective view of the controlling tank.

Figure 4 is a top plan view of said tank, the engaged portion of the pump casing being shown in section.

Figure 5 is a section on line 5—5, Figure 4, taken through the tank.

Figure 6 is a horizontal section through the tank and the adjacent portion of the pump casing.

Referring to the figures by characters of reference 1 designates a windmill structure of any preferred make into which projects the upper portion of a well casing 2 having a pump rod 3 adapted to be driven by the windmill by any suitable mechanism provided therefor. Such mechanism includes any preferred type of brake adapted to be actuated by a brake line 4. These features of the invention are all well known in the art and for that reason it is not deemed necessary to describe or illustrate them in detail.

A storage reservoir 5 can be located at any point desired and can be joined to one or more troughs 6 or the like by any suitable arrange-

ment of pipes 7, it being understood that the usual float controlled valve 8 can be employed in the trough for shutting off the supply of liquid thereto when the level thereof rises to a predetermined point.

Reservoir 5 communicates with the upper portion of the well casing 2 through a pipe 9 and that end of this pipe which opens into the reservoir is likewise provided with a valve 10 the operation of which is controlled by a float 11. These parts are so constructed and arranged that when the level of the liquid in the reservoir reaches a predetermined height, float 11 will close valve 10.

A tank 12 formed preferably of sheet metal is mounted to slide longitudinally along that portion of the well casing 2 located within the structure 1. This tank may be substantially semi-cylindrical, as shown or can be of any other preferred configuration. In practice it is designed to form a channel 13 in one wall of the tank 20 extending from top to bottom thereof, this channel being proportioned to receive a portion of casing 2 so that said casing can thus be used as a guide or track along which the tank can slide. For the purpose of holding the tank to the casing 2, retaining straps 14 can be attached to the tank 12 and embrace the casing loosely.

Tank 12 is preferably open at the top and is of course closed at the bottom. The top edges of the walls can be suitably reenforced, as indicated at 15 and reenforcing rods 16 or the like can be located along the bottoms of the tank walls. Likewise combined reenforcing and wear strips 17 can be secured along the surface of the guide channel 13 for contact with the casing and for stiffening the tank. Connecting ears or lugs 18 are secured to the walls of the tank adjacent its upper end and these are joined by upwardly converging cables or rods 19 to the lower end of the brake line 4.

An outlet nipple 20 is extended downwardly from the bottom of the tank 12 and is connected to one end of a flexible hose 21 the other end of which is joined to a nipple 22 opening into the pipe 9. The hose 21 is of sufficient length to permit efficient up and down movement of tank 12 on casing 2 to operate the brake of the windmill to either stop or release the mechanism.

It will be obvious, of course, that when the brake mechanism of the windmill is released, the tank 12 will be supported in an elevated position by the usual spring-restrained brake mechanism, this tank being empty under such conditions. As the windmill operates it will reciprocate the pump rod 3 and elevate liquid within casing 2 so that

it will be delivered through pipe 9 into the reservoir 5. When the liquid reaches the predetermined level within this reservoir, the float operated valve 10 will close. Thus further actuation of the pump by the windmill will cause the delivered liquid to flow upwardly through hose 21 into tank 12 and as this tank is gradually filled, the weight of the liquid added thereto will cause the tank to move by gravity from an elevated position, as shown in Figure 2, to a lowered position as shown in Figure 1. This movement will be sufficient to actuate the brake line 4 with the result that the brake mechanism will be operated to stop the actuation of the windmill.

15 As the supply of liquid is drawn from the reservoir 5 and the level of the liquid lowered, valve 10 will be opened and the surplus liquid contained within tank 12 will drain downwardly through hose 21 to pipe 9 thence into the reservoir 5. As 20 the liquid is thus withdrawn from the tank said tank will ascend under the action of the spring-controlled brake mechanism so that the windmill will be released from the action of the brake and can begin operation to again hoist liquid and deliver it to the reservoir. Thereafter the operation will be the same as has already been described.

25

In Figure 1 the spring of the brake mechanism which operates through said mechanism to hold the tank 12 normally elevated, has been shown at 23.

It has been found that the mechanism herein described is especially useful in connection with windmills employed for pumping water but obviously it can be employed wherever a motor-driven pump is to be employed for elevating any kind of a liquid other than water.

10 What is claimed is:

A brake-actuating means for pumps or the like including a tank open at the top, upwardly converging means connected to the walls of the tank for attachment to a brake line, said tank having 15 a flat wall and an arcuate wall, there being a channel extending from top to bottom of the tank within the flat wall, reinforcing means extending along the upper edge of the tank to hold the open end of the tank against collapse, combined 20 reinforcing and wear strips extending longitudinally along the wall of the channel, spaced arcuate means bridging the channel and secured to the tank, and a guide positioned between said strips and the wall of the channel.
